UNITED STATES PATENT OFFICE.

FREDERICK LAIST AND LABAN ELLSWORTH JONES, OF ANACONDA, MONTANA,
ASSIGNORS TO ANACONDA COPPER MINING COMPANY, A CORPORATION OF
MONTANA.

ROOFING STRIP.

Application filed October 21, 1921. Serial No. 509,286.

To all whom it may concern:

Be it known that we, FREDERICK LAIST and LABAN ELLSWORTH JONES, citizens of the United States, residing at Anaconda, in the county of Deer Lodge, and State of Montana, have invented certain new and useful Improvements in Roofing Strips, of which the following is a specification.

This invention relates to roof covering of metal.

It is well known that roof covering of any kind, if applied in large sheets to pitched roofs, presents an unsightly appearance repulsive to the eye and more or less destroys what artistic effects other parts of the building would have. Thus large sheet roof coverings are practically out of the question in connection with pitched roofs. The expedient of pressing the sheets to give them shingling effect is insufficient for the purpose.

The practice generally in vogue is therefore to apply the covering in relatively small strips or shingles. In order to produce the shingling effect and at the same time afford satisfactory protection against driving rain, the strips or shingles are laid above each other in overlapping relation and thus the covering may consist in substance of several layers of metal.

It is the object of this invention to provide roof covering of metal of such design and construction as to procure a maximum covering area with a given weight and thickness of metal and at the same time produce the square butt effect of a typical shingled roof.

For a full understanding of the invention reference is made to the accompanying drawing in which

Fig. 1 is a perspective sectional view vertically through a plurality of strips

Fig. 2 is a section on a larger scale showing the joint shown in Fig. 1;

Fig. 3 is a transverse section through two adjoining strips;

Fig. 4 is a plan view of a strip.

Fig. 5 is a plan view of a blank illustrating the first step in the formation of the finished product;

Fig. 6 is a similar view illustrating another step; and

Fig. 7 is an end take at right angles to Fig. 6.

Having reference to Figs. 1 to 4, 1 repre-

sents one unit of a relatively large number of strips of which the roofing may be composed. The dimensions and the proportion of length and width may vary within relatively wide limits. We have found that a strip of about 6' in length and 8" in width is best suited for most cases and may be considered as typical.

The strip has along its top edge a portion bent upon itself in the form of a loop 2 which itself is bent upon the main portion of the strip and spaced therefrom slightly more than the thickness of the strip. The free end projecting upwardly from the loop 2 is provided with a plurality of nail holes 3, say 8" apart.

Along the lower edge the strip 1 is bent twice to define two portions 4 and 5 respectively. The portion 4 is just long enough to fill the space between the main portion 75 of the strip and the loop 2 of a strip immediately below strip 1 and the portion 5 is wide enough to extend around the end of the loop 2.

In practice we prefer to form the end of the loop 2 square and the portion 5 correspondingly to imitate the square butt effect of a shingled roof. This arrangement also has a reinforcing effect inasmuch as it normally resists ordinary forces tending to crush the butt portion thus formed.

At the ends the strip is provided with turned over portions or tongues 6 and 7 respectively. The portion 6 is turned over the upper surface while the portion 7 is turned over the lower surface, both forming channels slightly larger than the thickness of the strips.

The mode of manufacturing the strip is preferably as follows:

From a strip of metal of the desired dimension portions 8 and 9 are cut out to produce a form having the shape shown in Fig. 5. The tongues 10 and 11 thus resulting are then bent back, tongue 10 over the upper surface and tongue 11 over the lower surface as indicated in Figs. 6 and 7. The purpose of these tongues is to laterally interlock adjacent strips and form a seal against ingress of water.

The application of the strips is obvious: Shingling is, as is usual, started at the bottom of the roof. Starting the operation from right to left one strip is laid down at the starting point and nailed down. Then

the tongue 11 of the next strip is entered into the channel defined by the tongue 10 of the first strip, pulled to the left and nailed down. All the other strips of the 5 first row are applied in the same way. The strips of the second row are then applied by interlocking tongues 10 and 11 of adjacent strips in the same way and at the same time pushing the portion 4 up into 10 the space between the loop 2 and the main portion on the strip or strips below. It is of course preferable to offset the strips in one row relatively to the strips in the adjacent rows. The other strips and rows of 15 strips are then applied in the same manner to the top of the roof.

The structural significance of the arrangement is as follows:

The loop 2 of one strip together with 20 the portions 4 and 5 of the next higher strip forms a seal through which the most violent driving rain cannot break. The seal constituted by the tongues 10 and 11 is likewise impregnable. The parts of the strips 25 through which nails are driven are absolutely protected so that no deteriorating action can start in that direction. The strips are so interlocked that wind-lifting is made impossible. 30 By providing these seals the amount of metal necessary to cover a given area exceeds the amount represented by a single sheet covering the area only by the relatively small amount necessary for forming 35 the seals. The percentage of extra metal necessary over and above the amount corresponding to a single sheet is very small and the cost of a roof is correspondingly decreased.

The covering area per pound of metal is 40 thus much greater than is possible with shingles laid according to the so-called American plan or according to the Diamond method.

The method of construction described furthermore has the advantage that the strips are free to expand and contract without injury to the finished roof as only one edge is secured by nailing.

Indentations or protuberances may be 50 made vertically in the strips in spaced relation to represent individual shingles.

We claim:

1. A metallic roofing strip having at its upper end a portion extending downwardly 55 in substantially parallel spaced relation to the body of the strip to provide a clearance, then outwardly substantially at right angle to the body of the main body, then upwardly and inwardly to points lying in 60 the plane of the strip slightly above the upper edge of the main body portion and then upwardly substantially in the plane of the main body portion.

2. A metal roofing strip according to 65 claim 1 having at its lower end a portion extending inwardly substantially at right angle to the main body portion and then upwardly substantially parallel to the main 70 body portion, the said clearance being such as to readily receive the upwardly extending portion at the lower end of another strip.

In testimony whereof, we affix our signatures.

FREDERICK LAIST.
LABAN ELLSWORTH JONES.
